UNITED STATES PATENT OFFICE

HARRINGTON CHAMBERS, OF FLUSHING, LONG ISLAND, NEW YORK

STAIR CONSTRUCTION

Application filed December 6, 1928. Serial No. 324,095.

This invention relates to stair construction and is directed more particularly to improvements in constructions for use in small dwellings.

It has heretofore been proposed to provide so-called disappearing stairways in small dwelling houses, such as bungalows or two story and attic dwellings. These stairways have been so constructed that they are normally elevated into the attic so as to leave the lower floor wholly unencumbered by their presence and they are adapted to be drawn down to the lower floor when it is desired to provide for passage between the floors. Such constructions have universally been built to be operated by cables wound around spring actuated drums which, when the stair is pulled down, serve to place the springs under tension for the purpose of counterbalancing the stair. Experience has proven, however, that these stairs, because of their cable suspension require a considerable amount of manual effort to operate and have not proven wholly satisfactory for this and other reasons well known to the trade.

With the foregoing considerations in mind, the object of the present invention is to provide a thoroughly simple and efficient construction which may be operated without any appreciable manual effort and which will be more strong and durable than prior constructions.

An important feature of the present invention consists in novel means for counterbalancing the stair, more particularly characterized by the fact that relatively long helical springs are utilized to act directly upon the stair construction instead of strong coil springs as heretofore used acting through cables.

My novel arrangement contemplates springs for counterbalancing the weight of the stair in a vertical direction, and separate springs for counterbalancing the stairs for sliding movement in the direction of their length and these springs are so proportioned as to their elasticity as to bring about a smooth cushioned operation with a minimum of manual effort.

A further feature of the invention consists in the employment of efficient means for locking the stair in its down position, so that it cannot inadvertently shift, but will provide at all times, when in such position, a safe passage between floors.

A feature of marked practical importance inherent in the present invention is the manner in which the stair is supported for pivotal movement and also partially for sliding movement. It has heretofore been common to mount the stair entirely on a trap door which in turn is hinged to the ceiling of the jamb of the stair well opening. Thus the weight of the entire structure is imposed on the hinges of the door. This results in a structurally weak arrangement.

According to the present invention, in contradistinction, a greater portion of the weight of the stair is carried by a shaft firmly anchored in the well opening and serving not only to carry the weight of the stair, but also providing a mounting for sheaves with which the counterbalancing springs cooperate. By the latter method a more secure mounting is obtained and installation of the stair may be more efficiently and expeditiously accomplished.

The stair of the present invention is, in its preferred form, provided at its upper end with a so-called top step or trip secured to the stringers of the stair by means of suitable metal brackets which also serve as a limiting means for the downward movement of the stair and as a mounting for the safety latch.

The foregoing features and others, hereinafter more fully described, result in a stair construction relatively simple to install, while highly efficient in the performance of its intended functions.

Features of the invention, other than those adverted to, will be apparent from the hereinafter detailed description and claims, when read in conjunction with the accompanying drawings.

The accompanying drawings illustrate one practical embodiment of the invention, but the construction therein shown is to be un-

derstood as illustrative, only, and not as defining the limits of the invention.

Figure 1 is a vertical section through stair construction embodying the present invention, the stair being shown in its "down" position.

Figure 2 is also a vertical section, partly broken away, showing the stair in an intermediate position.

10 Figure 3 shows the stair in an "up" or compacted position.

Figures 4 and 5 are detail sections showing parts of the stair removed and illustrating more particularly the manner in which 15 the stair and door are counterbalanced.

Figure 6 is a section on the line 6—6 of Figure 3.

Figure 7 is a section on the line 7—7 of Figure 3.

20 Figure 8 is a somewhat enlarged vertical section taken in approximately the plane of the line 8—8 of Figure 6 with part of the stair broken away and showing the mechanism for mounting the stair on the trap door 25 and in the well opening in elevation.

Figure 9 is a detail view showing the manner of anchoring the ends of the springs on the stair and jamb.

20 Figure 10 is a vertical section through the upper end of the stair.

For the purpose of concrete description, let it be assumed that 1 designates the floor level of a lower floor and that 2 designates the floor level of an upper floor. 3' designates the ceiling of the upper floor 2 and 4 the well opening in the upper floor 2. This well opening is provided with a suitable jamb 3 and with which jamb is associated a suitable finishing strip 5. The well opening

40 4 is provided with a trap door 6 hinged at 7 to the jamb 3 and adapted to swing on these hinges from a position wherein the trap door will close the well opening as shown in Fig. 3 into the downwardly inclined position shown in Figure 1 and vice versa. This trap door is made of strong, rigid construction and is preferably longitudinally and transversely strengthened by suitable stiffening 45 braces designated 8.

50 Extending transversely across that end of the well opening at which the door is hinged is a shaft 9. This shaft is firmly secured in place by means of brackets 10 as shown in Figure 6, so as to be rigidly mounted in position and to extend for the full width of the opening. On this shaft are mounted four sheaves which are designated 11, 11 and 12, 12. All of these sheaves are intended for cooperation with long coil springs, the purpose of which is to counterbalance the stair and door.

Two springs are employed for each of these purposes, those designated 14 serving to counterbalance the pivotal movement of 60 the door and stair while the springs 15 func-

tion to counterbalance the longitudinal movement of the stair. As shown best in Figure 4, one end of each of the springs 14 is anchored to a bracket 16 mounted on the jamb 3 of the well opening from whence the spring extends in the direction of the shaft 9 and passes about one of the sheaves 11, from whence it extends to and over a sheave 17 mounted on a bracket 18 also supported on the jamb 3. Beyond the sheave 17 the spring 14 extends downwardly and is anchored to the free end of the trap door as shown at 19 in Figs. 1, 3 and 7. The spring is always under sufficient tension to lift the door into the closed position shown in Fig. 4 and to maintain it seated against a door stop 20 associated with the jamb 3. Figure 9 shows the anchorage construction for the spring ends. A shackle or link 18a serves to secure each spring to its bracket 18 or 19 for slight pivotal movement so that there will be a straight pull on the shackles at all times, irrespective of the angle at which it is exerted.

The stair embodies parallel stringers 21 of suitable length and between the stringers extend the treads 22. The stair may be provided with risers if desired although as shown in the drawings the risers are omitted. Hand rail posts 23 are secured to the stringers and support a hand rail 24. One of these hand rails may be positioned at each side of the stair if desired. The stair is mounted for movement in the direction of its length upon rollers associated with the trap door and with the shaft 9. These rollers are best shown in Figures 6, 7 and 8. Rollers 25 are mounted on the shaft 9, so as to underlie the lower edges of the stringers and to provide for rolling coaction between these rollers and stringers. Similar rollers 26 are mounted on brackets 27 fixed to the free end of the door 6 and are also adapted to underlie and support the stringers of the stair.

Each stringer is provided in its outer face with a longitudinally extending guide channel 28, and on the brackets 27 are mounted guide pins 29 which extend into these channels. Guide brackets 30 are also mounted on the shaft 9 and each of these brackets carries a guide bar 31 which also fits into one of the channels 28. The guide pins 29 and the guide bars 31 engage the walls of the guide channels 28 in both of the stringers and hold these stringers in engagement with the rollers 26 and 25, respectively, while these rollers support the weight of the stair and at the same time permit movement of the stair in the direction of its length. Flanges 27a and 30a preclude lateral shifting of the stair with respect to the rollers so that the under edges of the stringers will cooperate with said rollers at all times. Suitable stops 32 limit the upward move-

ment of the stair through engagement with the brackets 27 as clearly shown in Fig. 8.

The stair is counterbalanced for movement in the direction of its length by the springs 15 hereinbefore referred to and the arrangement of which springs is clearly shown in Fig. 5. In this figure, one end of each of the springs 15 is secured to one of the brackets 18 which carries the sheaves 17 by the shackles or links as shown. Each of these springs 15 extend to and about one of the sheaves 12 mounted on the shaft 9 and from thence extend to and are secured to brackets 32 mounted on the outer sides of the stringers 21 of the stair. These springs 15 are always under tension and their purpose is to impart a sufficient upward pull upon the stair as to substantially counterbalance the weight of the stair when in down position. In other words, these springs are sufficiently strong, so that the stair may be moved vertically by manual manipulation without requiring the expenditure of appreciable manual force in this connection.

Similarly the springs 14 are sufficiently strong to carry the greater portion of the weight imposed on the trap door 6, so that the door may be opened or closed by the application of relatively little manual effort. It will be noted, however, that the spring 15 is somewhat shorter than the spring 14. Consequently it will be of correspondingly greater tension. The relation of the lengths of the springs is such that operations of the respective parts will be properly adjusted to one another.

Under normal conditions when it is desired that the stair be in an up position and out of the way, the parts are as illustrated in Fig. 3. It will be noted from this view that the trap door 6 is closed and that the stair is in substantially horizontal position in for example the attic.

In order to have access to the stair from the lower floor a pull cord or chain 33 is associated with the trap door. When a downward pull is manually exerted upon this chain, the door is swung downwardly on its hinges 7 into substantially the position shown in Fig. 2. When the door is thus tilted downwardly, the stair will slide down to within approximately one foot of the lower floor due to gravity or inertia. The balance of the downward movement requires slight manual effort. As the stair reaches its completely lowered position indicated in dotted lines in Figure 2, it is adapted to be locked in this position by suitable latches next to be described.

In order to provide proper landing between the upper end of the stair and the upper floor, the extreme upper end of the stair is preferably provided with a top step 22a supported on the stringers by metal

plates 36 in such manner that when the stair is in down position the top of the step 22a will be flush with the upper floor level. These plates are shown best in Fig. 10. They are preferably made as shown so that they can be used as either "rights" or "lefts". Each plate is secured to one of the stringers by screws 37 and to the top step 22a by screws 38. The recesses 39 are so positioned that when the stair is let down, stop pins 35 will enter into the recesses and positively stop the stair against further downward movement. Pivoted adjacent one of the recesses 39 is a latch 34, its pivot 40 being carried by the plate 36 and positioned above and on about the line of the lower edges of the stringers. The latch is a gravity latch and it is provided with a recess 39a. The lower edge of the latch is also formed with a cam surface 41 leading to this recess.

When the stair is moved downwardly, the pin 35 engages with the cam surface 41 and causes the latch to be lifted to permit the pin to enter both the recesses 39 and 39a in the plate and latch. As soon as this occurs the latch drops by gravity and locks the pin in place. An adjustable stop screw 42 is carried by the latch to control the locking position of the latch with respect to the pin so that the latch can be tripped to disengage the pin 35 by imparting to the stair a sudden upward thrust. This will swing the latch up and release the pin to permit elevation of the stair. The locking and unlocking positions of the latch are clearly shown in Fig. 10. The plates 36 are stamped or offset slightly as indicated at 43 so as to clear the stair guides 30a.

It will be apparent from the foregoing detailed description that the stair construction of this invention may be economically built and that it may be installed not only during the initial construction of houses, but it may also be installed in old houses without appreciable change in the building construction. The arrangement is easily operated without appreciable manual effort.

When the stair is in down position, it provides a rigid, safe and convenient means of access to the upper floor and does not embody the hazard incident to the employment of ladders and the like. The stair of the present invention is as safe to ascend and descend, when locked in down position, as a built-in stairway and yet it embodies all the advantages inherent in its ability to be moved into an out of the way position when not in use. The invention is particularly intended for use in small dwelling houses, bungalows and the like, but I do not restrict the invention to this use as it may be employed in loft buildings or other structures where such an arrangement would be desirable. The structure has

been described and illustrated as made of wood although it may be made of metal without departing from this invention, the scope of which is to be understood as fully 5 commensurate with the appended claims.

Having thus fully described the invention, what I claim as new and desire to secure by Letters Patent is:

1. In a stair construction adapted to be used between lower and upper floors, the latter of which is provided with a stair well opening, a trap door adapted when in horizontal position to close the opening and which door is hinged to be opened into a 10 downwardly inclined position, guide rollers mounted near the free end of the door, a shaft extending across the well opening at the end thereof at which the door is hinged and which shaft is supported at its opposite 15 ends on the jamb of said well opening, rollers carried by said shaft, a rigid stair embodying stringers and treads mounted with the lower edges of the stringers bearing upon the rollers on the door and shaft to 20 mount said stair for longitudinal movement, said stringers being provided with longitudinal guides, guide members associated with the rollers and engaging with the 25 guides to hold the stringers in engagement with the rollers, helical coil springs for 30 counterbalancing the weight of the stair in the direction of its length and the weight of the door and stair in a substantially vertical direction, and locking means to lock 35 the stair in its lowered position against inadvertent lifting movement.

2. In a stair construction adapted to be used between lower and upper floors, the latter of which is provided with a stair well 40 opening, a trap door adapted when in horizontal position to close the opening and which door is hinged to be opened into a downwardly inclined position, guide rollers mounted near the free end of the door, a 45 shaft extending across the well opening at the end thereof at which the door is hinged and which shaft is supported at its opposite ends on the jamb of said well opening, rollers carried by said shaft, a rigid stair 50 embodying stringers and treads mounted with the lower edges of the stringers bearing upon the rollers on the door and shaft to mount said stair for longitudinal movement, said stringers being provided with longitudinal 55 guides, guide members associated with the rollers and engaging with the guides to hold the stringers in engagement with the rollers, helical coil springs for counterbalancing the weight of the stair in the direction 60 of its length and the weight of the door and stair in a substantially vertical direction, said stair being provided at its upper end with attaching plates secured to the stringers and provided with recesses, a top step 65 secured to the attaching plates, a detent also

provided with a recess pivotally mounted on one of said attaching plates, a pin mounted on one of said guides and which pin is adapted to actuate the latch to enter the recesses of the latch and attaching plate to lock the stair in its down position, and an adjusting member for adjusting the latch for proper engagement with the pin. 70

3. In a stair construction adapted to be used between lower and upper floors, the latter of which is provided with a stair well opening having a hinged trap door therein, a rigid stair mounted for sliding movement longitudinally of the door and embodying stringers and treads, helical coil springs interposed between the stair and a relatively fixed anchorage at the upper floor to counterbalance the weight of the stair in the direction of its length, and additional helical coil springs interposed between the door and a relatively fixed anchorage at the upper floor to counterbalance the weight of the stair and door in a substantially vertical direction, said latter springs being wholly 80 separate and independent in operation of the said springs to counterbalance the weight of the stair in the direction of its length. 85

4. In a stair construction adapted to be used between lower and upper floors, the latter of which is provided with a stair well opening having a hinged trap door therein, a rigid stair mounted for sliding movement longitudinally of the door and embodying stringers and treads, helical coil 90 springs interposed between the stair and a relatively fixed anchorage at the upper floor to counterbalance the weight of the stair in the direction of its length, and additional helical coil springs interposed between the door and a relatively fixed anchorage at the upper floor to counterbalance the weight of the stair and door in a substantially vertical direction, said latter springs being wholly 95 separate and independent in operation of the said springs to counterbalance the weight of the stair in the direction of its length. 100

5. In a stair construction adapted to be used between lower and upper floors, the latter of which is provided with a stair well opening having a hinged trap door therein, guide rollers mounted near the free end of the door, a shaft extending uninterruptedly across the well opening at the end thereof at which the door is hinged and which shaft is supported at its opposite ends on the jamb on opposite sides of said well opening, rollers carried by said shaft, a rigid stair embodying stringers and treads mounted with the lower edges of the stringers bearing upon the rollers on the door and shaft to mount said stair for longitudinal move- 115 120 125 130

- ment, helical coil springs secured to the stair and jamb for counterbalancing the weight of the stair in the direction of its length, and helical coil springs, separate 5 from and independent of the said coil springs of the stair and jamb, secured to the jamb and door for counterbalancing the weight of the door and stair in a substantially vertical direction, whereby the stair 10 is counterbalanced in the direction of its length independently of its counterbalancing in a substantially vertical direction.
6. In a stair construction adapted to be used between lower and upper floors, the 15 latter of which is provided with a stair well opening having a hinged trap door therein, guide rollers mounted near the free end of the door, a shaft extending uninterruptedly across the well opening at the 20 end thereof at which the door is hinged and which shaft is supported at its opposite ends on the opposite sides of the jamb of said well opening, rollers carried by said shaft, sheaves also mounted on said shaft, a rigid 25 stair embodying stringers and treads mounted with the lower edges of the stringers bearing upon the rollers on the door and shaft, to mount said stair for longitudinal movement, coil springs, one end of each of 30 which is secured to the stair and which coil springs extend around the sheaves and are suitably anchored with respect to the well jamb to counterbalance the weight of the stair in the direction of its length, and ad- 35 dditional coil springs, one end of each of which is secured to the jamb, and which latter springs extend around the sheaves and are secured at their other ends to the door adjacent its free end, to counterbal- 40 ance the weight of the stair and door in a substantially vertical direction, and additional directional sheaves coacting with the last mentioned springs between the sheaves on the shaft and the free end of the door 45 and which directional sheaves are supported on the well jamb, whereby the weight of the stair in the direction of its length is counterbalanced independently of the weight of the stair and door in a substantially ver- 50 tical direction.
7. In a stair construction adapted to be used between lower and upper floors, the latter of which is provided with a stair well opening having a hinged trap door therein, 55 a rigid stair mounted for sliding movement longitudinally of the door and embodying stringers and treads, helical coil springs interposed between the stair and a relatively fixed anchorage at the upper floor to coun- 60 terbalance the weight of the stair in the direction of its length, and additional helical coil springs interposed between the door and a relatively fixed anchorage at the upper floor to counterbalance the weight of the 65 stair and door in a substantially vertical
- direction, said latter springs being wholly separate and independent in operation of the said springs to counterbalance the weight of the stair in the direction of its length, and the springs which counterbalance the weight 70 of the stair in the direction of its length being of a different tension than the springs which counterbalance the weight of the stair and door in a substantially vertical direction. 75
